UNITED STATES PATENT OFFICE.

GEORGE J. THEOBALD, OF BOSTON, MASSACHUSETTS, ASSIGNOR, BY DIRECT AND MESNE ASSIGNMENTS, OF TWO-THIRDS TO HARRY H. REED, OF BOSTON, MASSACHUSETTS.

CART-SADDLE FOR HARNESS.

No. 851,784.

Specification of Letters Patent.

Patented April 30, 1907.

Application filed October 17, 1906. Serial No. 339,332.

To all whom it may concern:

Be it known that I, GEORGE J. THEOBALD, a citizen of the United States, residing at Boston, county of Suffolk, and State of Massachusetts, have invented an Improvement in Cart-Saddles for Harnesses, of which the following description, in connection with the accompanying drawings, is a specification, like letters on the drawings representing like parts.

This invention relates to cart saddles for harnesses and has for its object to provide a novel saddle which may be readily adjusted to fit horses of different shape without rendering the saddle bulky and without the necessity of using large and thick pads.

The invention also has for its object to provide a ventilated pad which will not become sweat-soaked and consequently hard as the stuffed pads now commonly in use will do.

In the drawings, Figure 1 is a view partly in section of my improved cart saddle; Fig. 2 is a bottom plan view of one side of Fig. 1. Fig. 3 is a perspective view of the locking member for holding both sections in adjusted position.

In the form in which I have herein chosen to illustrate my invention, the usual bow to which the pad holders are secured is made in two sections which are hinged to each other or flexibly connected together, and each section carries one of the pads, so that by moving the bow sections relative to each other the pads may be adjusted to fit horses of different shapes. The two sections of the bow are designated in the drawings by 3 and 4 respectively, and they are flexibly connected at their inner ends in some suitable way as by a hinge 5 or its equivalent. 6 is the usual chain which passes over the bow and lies in a groove or channel therein. This chain leads to the thill straps as usual.

Secured to each section of the bow is a pad support 7 of any suitable or usual construction to which the pad is secured. The pad herein shown is of novel construction, it comprising a hollow perforated member 8, preferably of metal which is carried by the pad support and which may or may not have a padded face as desired. When in place this perforated member is spaced from the pad support, thereby forming between it and said pad support a chamber 10 which being

filled with air serves to keep the pad thoroughly ventilated. The face of the perforated member 8 may be covered with any suitable padding 11, such as felt, hair, or any other material, or said pad may be used without any exterior padding, in which case the perforated face of the foundation would rest directly on the horse. The pad supports 7 are rigidly secured to the bow in any suitable way, as by means of screws 12.

By making the bow in two sections 3 and 4 which are joined together, as at 5, the pads 6 may be adjusted toward and from each other to fit the back of any horse, and because of this adjustment it is not necessary to use such thick heavy padding of hair or felt as is the case where the saddle structure is a rigid one. If the horse is a fat, round horse, the two sections of the bow may be adjusted to the full line position Fig. 1, while if the horse is thin or has a sharp back, the section of the bow may be adjusted into the dotted line position thus carrying the pads nearer together and into position to fit the horse's back. It is desirable to provide for locking the sections of the bow in any adjusted position, and for this purpose I have provided the lock 13 which is made so that it will both lock or hold both sections in adjusted position and serve to stiffen the bow at the joint. For this purpose I prefer the form of lock shown in Fig. 3 which comprises the two side flanges 18 that are connected by the bridge-piece 17. The side flanges 18 straddle the bow section 3 and are pivoted thereto, as at 14, and one of said side pieces is provided with notches 15 which are adapted to fit over a pin or projecton 16 extending laterally from the bow section 4. By bringing any one of the notches 15 into engagement with the pin 16, both sections can be held at the desired angle relative to each other. The two side flanges 18 of the lock just fit against the sides of the bow, and as said side pieces bridge the joint of the bow they serve to hold the bow sections in abutment and prevent them from twisting relative to each other sufficiently to put any undue strain upon the hinge 5. It will be noted that the chain 6 extends under the bridge-piece 17, and the latter, therefore, serves as a means for holding the chain in place. This form of lock, therefore, is one which acts both to hold the

bow sections in adjusted position relative to each other, and also acts to stiffen the joint and prevent the bow sections from twisting.

The above construction of pad is one which 5 will not become sweat-soaked and stiff as the solid pads of hair, felt, etc. now in common use.

The drawings show one embodiment only 10 of my invention, and therefore the latter is not limited to the constructional details herein shown.

Having fully described my invention, what I claim as new and desire to secure by Letters Patent is:—

- 15 1. In a cart saddle, the combination with a grooved bow made in two sections jointed together and means at the joint of the bow to hold the bow sections in adjusted position and to hold the chain in the groove of the bow, of a pad support rigidly secured to each section, a perforated metal member secured to each pad support and spaced therefrom, and a padding covering the face of the perforated metal member.
- 20 2. In a cart saddle, the combination with a grooved bow made in two sections jointed together of a pad support rigidly secured to each section, a perforated metal member secured to each pad support and spaced therefrom, a padding covering the face of the perforated metal member, and a pivoted notched locking device carried by one bow section and adapted to embrace the other section and to engage projections thereon thereby to hold the sections in adjusted position.
- 25 3. In a cart saddle, the combination with a grooved bow made in two sections jointed

together of a pad carried by each section of the bow, and a lock hinged to one bow section, said lock comprising two side flanges which overlie the sides of the bow section, one of which has notches to engage a projection extending from the other bow section.

4. In a cart saddle, the combination with 45 a grooved bow made in two sections jointed together of a pad carried by each section of the bow, and means shaped to embrace the bow sections at the joint of the bow and adapted both to hold the bow in adjusted 50 position and to prevent the sections of the bow from twisting.

5. In a cart saddle, the combination with 55 a grooved bow made in two sections jointed together of a pad carried by each section of the bow, and means at the joint of the bow both to hold the bow sections in adjusted position and to hold the chain in the groove of the bow.

6. In a cart saddle, the combination with 60 a grooved bow made in two sections jointed together of a pad carried by each section of the bow, a chain occupying the groove of the bow, and a lock hinged to one bow section and having two side flanges which overlie the 65 sides of the bow and which are connected by a bridge that extends across the groove, one of said flanges having notches to engage a projection extending from the bow section.

In testimony whereof, I have signed my 70 name to this specification, in the presence of two subscribing witnesses.

GEO. J. THEOBALD.
